[57] CLAIM

The ornamental design for a dual jewelry box, as shown and described.

DESCRIPTION

FIG. 1 is a top view of a dual jewelry box, with its lid closed, showing my new design;

FIG. 2 is a top view of the dual jewelry box, with its lid open;

FIG. 3 is a top plan view of the dual jewelry box with its lid closed;

FIG. 4 is an elevational front view of the dual jewelry box;

FIG. 5 is an elevational side view of the dual jewelry box;

FIG. 6 is an elevational rear view of the dual jewelry box;

FIG. 7 is an elevational side view of the dual jewelry box, opposite that of FIG. 5;

FIG. 8 is a bottom plan view of the dual jewelry box.
